United States Patent Office

Des. 191,696
Patented Nov. 7, 1961

191,696

BELT BAG

Frederick R. Weil, 65 Utica St., Clinton, N.Y.

Filed July 2, 1956, Ser. No. 42,110

Term of patent 3½ years

(Cl. D3—10)

Fig. 1

Fig. 2

Fig. 3

FIG. 1 is a perspective view of a belt bag showing my new design;

FIG. 2 is an inside elevational view thereof as it appears extended; and

FIG. 3 is a fragmentary view showing one of the bag members partially broken away to reveal the interior thereof.

I claim:

The ornamental design for a belt bag, as shown.
